UNITED STATES PATENT OFFICE

JULIUS FISCHER DE TOVÁROS, OF BUDAPEST, HUNGARY

CURRENT COLLECTOR FOR ELECTRIC RAILWAYS

Original application filed July 17, 1925, Serial No. 44,298, now Patent No. 1,744,622, dated January 21, 1930, and in Hungary July 23, 1924. Divided and this application filed October 29, 1929. Serial No. 403,268.

The present invention relates to a current collector for electric railways comprising a sliding shoe having a flat wide contact surface and swingably or pivotally carried on a frame adjusted at an acute angle to the trolley wire in order to ensure a complete contact on said wire along the whole width of the contact surface. The frame is fitted in known manner on a frame arranged on the vehicle top, preferably on a swinging scissor current collector frame, and can be reversed on changing the direction of travel.

For sliding plates or shoes of such current collectors counterweights or springs are provided which prevent a tilting of the sliding shoe, that is, which tend to bring back the contact surface of the shoe continuously into the horizontal position.

Hitherto, the counter-balancing weights or return springs were arranged at the upper end of the inclined swinging frame carrying the sliding shoe, so that they acted directly on the shoe. This arrangement, however, on the one hand increases the weight, that is, the inertia of the sliding shoe so that this cannot follow sufficiently quickly the small deviations of the trolley wire from the horizontal during the journey, and on the other hand the kinetic energy of the masses of the return or counterbalancing weights acts on the deflection of the swinging inclined frame all the stronger the closer the centre of gravity of this weight approaches the upper end of the swinging frame. In addition the return weight arranged at the top causes, particularly with high speeds, a somewhat considerable air resistance.

The invention is a division of my prior application Serial No. 44,298, filed July 17, 1925, now Patent No. 1,744,622, granted January 21, 1930, and it has for its object to transfer the return springs or weights to the vicinity of the lower link of the swinging frame and thus overcome the above mentioned defects.

This is effected according to the invention by providing on one side of the swinging frame or of the sliding shoe a hinged parallelogram, the two adjacent sides of which are formed by the shoe and the frame, while

the other two adjacent sides are formed by a tension or compression member and a controlling lever for the shoe to which the return spring or the return weight is connected.

On the drawing two ways of carrying out the invention are illustrated.

Figures 1 and 2 show one form of construction in side view, in the two travelling directions.

Figure 3 shows the second form of construction in one travelling direction.

Figure 4 is an explanatory sketch of the link parallelogram of the second form of construction.

In Figures 1 and 2, k_4 and k_5 are the rods forming the top link O_2 of a scissor current collector frame to which is hinged the inclined swinging frame k . This latter carries the shoe a which is swingably carried at the upper end of the frame k about the axis o by means of the bearings n , so that the flat wide contact surfaces of the shoe a may lie closely to the trolley wire v in any angular position of the frame k .

The frame k has an extension k_2 to which are connected the springs r_1 r_2 . The frame k can be reversed from the position shown in Figure 1 to the position corresponding to the other direction of travel, the adjusted position being ensured by one or the other of the springs r_1 or r_2 .

The link parallelogram according to the invention is formed in such manner that the shoe a is hinged at a point o_1 lying outside its axis of oscillation o , by means of a tension or compression member, for example the rod k_1 , with a control lever k_3 at O_3 , which lever is rotatably carried in the vicinity of the top link o_2 , or, according to the drawing, on the top link o_2 itself. The stud of the link o_1 is fitted on a small carrier s which is connected with the shoe for example by means of rivet d sunk in its lubricating groove.

The control lever k_3 is rigidly connected with an arm k_6 at the lower end of which are connected the return springs r_3 , r_4 , which may also be replaced by a weight.

With oscillations of the frame k the link apparatus k_6 , k_3 , o_3 , k_1 , o_1 holds the contact surface a continuously in approximately

horizontal position so that it bears closely against the trolley wire v . The connection at the link o_1 or o_3 (in Figure 1 at o_3) is preferably effected by forming a slot in the rod k_1 with a certain amount of play, so that the shoe can adapt itself to slight deviations of the trolley wire from the horizontal position without transmitting these slight deviations to the control lever k_3 .

10 The parallelogram described permits the adjustment of the sliding shoe corresponding to the changes in direction of the trolley wire in vertical plane and the use of an inclined reversible frame k on a current collecting frame without requiring upper return weights or

15 springs. The form of construction according to Figure 3 only differs from the first construction by the length of the control arm k_3 being larger than the rotating arm o , o_1 of the tension or compression member k_1 acting on the shoe and connecting the latter with the control arm k_3 . This form of construction is for the following purpose:

20 In cases where the inclined resultant indicated by R in Figure 3, of the pressure and the friction on the trolley wire does not pass through the rotating axis of the sliding shoe, a turning moment about the axis of rotation o of the shoe is exerted by this resultant tending to depress the back half, in the direction of travel, of the shoe and thus to raise the front half. Consequently the pressure along the width of the contact surface is unequal, being greater at the front part, which causes a premature wear of the latter.

25 If now the arm k_3 is lengthened so that a parallelogram with unequal sides is produced and the point o_3 is caused to lie at o'_3 (Figure 4) then with the same length of the tension or compression member k_1 , and exactly for the reason of its length remaining the same, an upward directed pressure is exerted on the back half, in the direction of travel, of the sliding shoe, which tends to transfer the point o_1 to o'_1 .

30 In this manner, a counter turning moment is created compensating the resultant R of the pressure and the friction on the trolley wire, thus producing during travelling an equal pressure over the whole width of the sliding shoe. In the reversed position of the frame k , a counter turning moment is obtained for the same reasons, which tends to draw the front edge, in the direction of travel, of the shoe downwards, that is, to take it away from the trolley wire. This has the same effect as the aforementioned upward pressure of the back edge of the shoe.

35 What I claim is:

1. A current collector for electric railways embodying a sliding shoe provided with flat wide contact surfaces and mounted to oscillate on a frame adjusted at an acute angle to the trolley wire, which frame can be reversed

on changing the direction of travel, characterized by a link parallelogram provided on one side of the frame or sliding loop capable of oscillation, two adjacent sides of which are formed by the shoe and the frame, and the other adjacent sides of which are formed by a tension or compression member and a controlling lever for the shoe, on which engages the return force.

2. Current collector according to claim 1, characterized by the length of the arm of the control lever forming the lower horizontal link of the parallelogram being greater than the part of the sliding shoe which forms the upper horizontal link of the parallelogram.

3. In testimony whereof I hereunto affix my signature.

JULIUS FISCHER DE TOVÁROS.
